(57) **CLAIM**

The ornamental design for a brushless impact driver, as shown and described.

DESCRIPTION

FIG. 1 is a top, rear and right side perspective view of a brushless impact driver showing my new design;

FIG. 2 is a right side elevation view thereof;

FIG. 3 is a left side elevation view thereof;

FIG. 4 is a rear elevation view thereof;

FIG. 5 is a front elevation view thereof; and,

FIG. 6 is a top plan view thereof.

The broken lines in the drawings illustrate portions of the torque wrench that form no part of the claimed design.
